HINGE

Harold J. Carlson, Union Pier, Mich., assignor to W. H. Miner, Inc., Chicago, Ill., a corporation of Delaware

Filed Feb. 5, 1962, Ser. No. 68,688

Term of patent 14 years

(Cl. D10—9)

Fig. 1

Fig. 2

Fig. 3

Fig. 4

Fig. 5

Fig. 6

FIGURE 1 is a perspective view of a hinge embodying my new design;

FIGURE 2 is a top plan view thereof;

FIGURE 3 is a side elevational view thereof;

FIGURE 4 is a bottom plan view thereof;

FIGURE 5 is an end elevational view, looking from the left hand end of FIGURE 3; and

FIGURE 6 is an end elevational view, looking at the right hand end of FIGURE 3.

I claim:

The ornamental design for a hinge, as shown.
